UNITED STATES PATENT OFFICE

HANS MATTES, OF ULM, GERMANY

TONGS FOR SPLITTING WOOD

Application filed November 2, 1929, Serial No. 404,377, and in Germany November 9, 1928. Renewed November 23, 1931.

My invention relates to a pair of tongs adapted for the splitting of wood and the like and having axe-shaped cutting blades, which are forced into the piece of wood to be split.

In the device according to this invention this operation is furthered, owing to the particular shape of tongs by a lever effect and by pushing it in the direction of the cleft, the splitting being accomplished with little effort and without any danger to the operator. These effects, according to the invention, are attained by suitably shaping the cutting edges, the bit of tongs, the short and long arms of the levers and by a suitable coordination of these single parts to each other.

In the drawings affixed to this specification and forming part thereof several modifications of tongs embodying my invention are shown diagrammatically by way of example.

In the drawings

Fig. 1 is a front elevation,

Fig. 2 is a side-elevation,

Fig. 3 a plan view, and

Fig. 4 a section on line A—B in Fig. 1 of the first modification.

Fig. 5 is a section on the same line of another modification, and

Fig. 6 is a side elevation thereof,

Figs. 7 and 8 show the manner of producing a particularly advantageous form of the cutting edge.

Figs. 9-11 represent a third modification and the manner of operating it.

Referring first to Figs. 1-4 the tongs comprise shanks *a* and *b* forming double-armed levers, and a pivot *c*. The short lever arms *d* terminate in axe-shaped cutting blades *e*, the cutting edges *f* of which, due to the stop *g*, are only permitted to approach to such an extent that they are still spaced from each other. The symmetrical planes of the cutting blades *e* coincide wholly or at least approximately, so that they can easily penetrate the wood.

In order to be able to seize the wood to be split at a suitable distance from its edge *h*, the symmetrical plane of the cutting blades includes an angle with the arms *d* of preferably 120° to 135° , which, however, in pro-

portion to the length of the arms *d* may be larger or smaller. In order that the cutting blades, while penetrating the wood, move as far as possible within their symmetrical planes without exerting transversal pressure, as is for instance the case with pliers, and that further, at the beginning of the impression, the lower points *i* of the cutting edges which, owing to their proximity to the axis of rotation *c* are capable of exerting the greatest power, will become active, the cutting edges *f* are preferably arranged vertically to the axis of rotation. A relatively small deviation, however, from the vertical, as for instance shown in the modifications according to the Figs. 9-11 would not matter.

The long arms *a* and *b* of the levers may be bent off from the plane of the cutting blades at a small angle contrary to the bending of the short arms *d* in order to keep the hand of the user at a distance *k* from the piece of wood.

Between the cutting blades *e*, the shanks *d* and the pivot *c* a wide space, preferably of square form, is provided which offers a free space for the split-off piece of wood during the operation to be described below. In practice the sides of this space should have a length of about 40 mms. the other dimensions of the tongs being chosen proportionally to the dimensions given in Figs. 1, 2 and 9.

At the lower side the cutting blades are formed with rounded or flattened edges, as at 1, so as to avoid their penetration into the wood when operated according to Fig. 11 (Figs. 1, 4 and 5).

The upper edge of the cutting blades may be shaped in a similar manner (*m* in Figs. 5 and 6).

The most advantageous form of the cutting members *f* is shown in the Figs. 7 and 8. Here the angle α at the upper edge *n* of the cutting blades is a relatively small one, in order to enable this edge, which is remote from the point of rotation, to penetrate tough wood, which does not burst under the pressure of the points *i*. The angle β , however, of the cutting edges at the lower part of the

cutting blades is relatively large, because here, owing to the more favourable leverage, it is possible to exert a greater power and the splitting of the wood is effected by 5 a more rounded or flattened point more rapidly and with more energy, and because by this formation the point which is mainly stressed, is well protected against deterioration. The planes bordering the cutting edge 10 of the blade, therefore, intersect the lateral surfaces *o* of the cutting blades on lines *p* which at the edge are spaced from the points *i*, but which at the upper edge nearly or wholly touch the cutting edges *f*. 15 In the modifications shown in Fig. 3 the cutting blades are symmetrical to a plane *q, r*. The manufacture and grinding of the tongs is simplified, if the cutting blades are unsymmetrically formed so that either the 20 outer or the inner faces *o* lie in a common plane, the grinding being effected according to Figs. 7 and 8, on one side only, preferably from the common plane. The action of the tongs will not be affected thereby. 25 The ends of the long arms of the lever may be provided with projections *s* preventing the hand from gliding off. A spring *t* may be provided for opening the tongs. 30 The operation and action of tongs according to this invention are as follows: The piece of wood to be split is seized at one of its ends with the tongs (Fig. 9) and the latter forced into it with the points *i* in 35 front. A piece of easily splitting wood of moderate length will already burst under this action. If the splitting be not yet accomplished it will be finished by lever-like lateral movements of the tongs in the direction of the arrow *v*, the piece *w* to be split extending into the space between the bits (Figs. 10 and 11). Corresponding to the facility with which the wood can be split, nearly the whole width and depth of the bit of tongs may be made use of. 40 If the splitting of the wood is not yet finished by the lateral lever movement, the tongs are shifted in their longitudinal direction in closed position, as shown in Fig. 11, which is highly facilitated by the truncation of the edges *l* or *m* (Figs. 4, 5) and in this new position the lever-like movement according to Figs. 9 and 10 is then repeated. It is possible in this manner to split pieces of wood 45 of any length with a single closing of the tongs. The shifting movement according to Fig. 11 may be carried out also from below upwards, especially if the cutting blades are formed as shown in Figs. 5 and 6. With 50 thin wood the lever movement in the sense of the arrow *v* (Fig. 9) may be dispensed with: here the tongs will only be closed and moved downwards or upwards in the sense of the arrow *x* (Fig. 11), thereby splitting the wood 55 without any further effort. This manner of

operation is especially adapted for the production of thin chips of wood.

If the tongs are produced approximately in the dimensions shown in Figs. 1 and 2, they may be operated without any effort and without any danger of hurting the operator, such as is the case with the use of knives or hatchets, and further without any injury to the clothes, and noiseless and in a very clean manner. Neither by the truncate wedge like edges provided below *l* and above *m*, nor by the points *i* which are closed during the shifting movements according to Fig. 11, can the operator be hurt. Injury to the tongs is avoided by the favorable shape of the cutting 75 edges.

I wish it to be understood that I do not desire to be limited to the exact details of construction shown and described for obvious modifications will occur to a person 80 skilled in the art.

In the claims affixed to this specification no selection of any particular modification of the invention is intended to the exclusion of other modifications thereof and the right 90 to subsequently make claim to any modification not covered by these claims is expressly reserved.

I claim:—

1. Tongs for splitting wood and the like, 95 comprising a pair of axe-shaped cutting blades extending substantially in the same plane, when the tool is closed, and a pair of double-armed levers, pivoted to each other, said blades being fixed to the shorter arms of 100 said levers at an angle so as to allow the piece of wood to be split to be gripped by the blades in the direction of its fibres with the longer lever arms extending sideways of the wood, additional blades being formed at the inner 105 ends of the main blades and extending substantially at right angles thereto, said additional blades enclosing obtuse angles with the blade body.

2. Tongs for splitting wood and the like, 110 comprising a pair of axe-shaped cutting blades extending substantially in the same plane, when the tool is closed, and a pair of double-armed levers, pivoted to each other, said blades being fixed to the shorter arms 115 of said levers at an angle so as to allow the piece of wood to be split to be gripped by the blades in the direction of its fibres with the longer lever arms extending sideways of the wood, additional blades being formed at the outer 120 ends of the main blades and extending substantially at right angles thereto, said additional blades enclosing obtuse angles with the blade body.

3. Tongs for splitting wood and the like, 125 comprising a pair of axe-shaped cutting blades extending substantially in the same plane, when the tool is closed, and a pair of double-armed levers, pivoted to each other, said blades being fixed to the shorter arms of

said levers at an angle so as to allow the piece of wood to be split to be gripped by the blades in the direction of its fibres with the longer lever arms extending sideways of the

5 wood additional blades being formed at the inner and outer ends of the main blades and extending substantially at right angles thereto, said additional blades enclosing obtuse angles with the blade body.

10 4. Tongs for splitting wood and the like, comprising a pair of double-armed handles, and a cutting blade at the shorter arm of each handle, each cutting blade having a pair of side faces intersecting at an angle 15 and a cutting edge defined by another pair of side faces intersecting at an angle which is larger than the angle of said first-mentioned side faces, the faces of said cutting edge being so arranged with respect to the

20 faces of said blade that their lines of intersection intersect at the apex of the angle included by said first-mentioned pair of side faces.

5. Tongs for splitting wood and the like, 25 comprising a pair of double-armed handles, and a cutting blade at the shorter arm of each handle, each cutting blade having a pair of side faces intersecting at an angle and a cutting edge defined by another pair of side 30 faces intersecting at an angle which is larger than the angle of said first-mentioned side faces, the cutting edges of said blades extending in a single plane, the faces of said cutting edge being so arranged with respect 35 to the faces of said blade that their lines of intersection intersect at the apex of the angle included by said first-mentioned pair of side faces, and means for keeping said cutting edges apart from each other when said tongs 40 are closed.

6. Tongs for splitting wood and the like, comprising a pair of double-armed handles, and a cutting blade at the shorter arm of each handle, said handles including an acute angle 45 with the plane in which said cutting blades are reciprocated, and each cutting blade having a pair of side faces intersecting at an angle and a cutting edge defined by another pair of side faces intersecting at an angle 50 which is larger than the angle of said first-mentioned side faces, the faces of said cutting edge being so arranged with respect to the faces of said blade that their lines of intersection intersect at the apex of the angle included by said first-mentioned pair of side 55 faces.

7. Tongs for splitting wood and the like, 60 comprising a pair of double-armed handles, an axe-shaped cutting blade at one end of each handle, a pivot connecting said handles and extending at right angles to the plane in which said cutting blades are reciprocated, the shorter arms of said handles being bent away from said cutting blades at an obtuse 65 angle, and the longer arms of said handle

including an angle with said cutting blades which is more acute than the angle at which said shorter arms are bent away from said cutting blades.

8. Tongs for splitting wood and the like 70 comprising a pair of double-armed handles, an axe-shaped cutting blade at one end of each handle, a pivot connecting said handles and extending at right angles to the plane in which said cutting blades are reciprocated, 75 the shorter arms of said handles being bent away from said cutting blades at an obtuse angle and defining a substantially square opening with said blades viewed in the longitudinal direction of said tongs, and the longer arms of said handle including an angle with 80 said cutting blades which is more acute than the angle at which said shorter arms are bent away from said cutting blades.

In testimony whereof I affix my signature. 85
HANS MATTES.
